UNITED STATES PATENT OFFICE.

HENRY W. HUFFMAN, OF HEMPHILL, TEXAS.

RAILROAD-TIE.

1,257,868.

Specification of Letters Patent. Patented Feb. 26, 1918.

Application filed August 7, 1916. Serial No. 113,618.

To all whom it may concern:

Be it known that I, HENRY W. HUFFMAN, a citizen of the United States, residing at Hemphill, in the county of Sabine and State 5 of Texas, have invented a new and useful Railroad-Tie, of which the following is a specification.

This invention relates to metallic railway ties, one of its objects being to provide an 10 all metal tie which is simple in construction, and which will provide a resilient support for the rails so that approximately the same cushioning effect is obtained as where wooden ties are employed.

15 A still further object is to provide simple and efficient means for fastening rails to the tie.

With the foregoing and other objects in view which will appear as the description 20 proceeds, the invention resides in the combination and arrangement of parts and in the details of construction hereinafter described and claimed, it being understood that changes in the precise embodiment of 25 the invention herein disclosed, can be made within the scope of what is claimed, without departing from the spirit of the invention.

In the accompanying drawings the preferred form of the invention has been shown.

30 In said drawings:—

Figure 1 is a side elevation of a tie embodying the present improvements, one of the rails and its fastening means being shown in position thereon.

35 Fig. 2 is a plan view of the structure shown in Fig. 1.

Fig. 3 is a section on line 3—3 Fig. 1.

Fig. 4 is a perspective view of one of the fastening wedges.

40 Fig. 5 is a similar view of the wedge with one end bent to prevent withdrawal of the wedge from engagement with a rail and tie.

Referring to the figures by characters of reference 1 designates the web of the tie 45 the same being provided, at each end, with oppositely extending base flanges 2. Extending into the web from each end of the tie is a longitudinal slot 3 located close to the bottom of the web and formed at the

50 top of the web and above each of the slots 3 is an enlargement 4 in which is provided a transverse recess 5 constituting a rail seat. The walls of the recess overhang the bottom thereof, as shown particularly in Fig. 1 and 55 formed in the bottom of each recess close

to the inner wall thereof is a key receiving depression 6 the walls of which overhang the bottom of the depression and the inner one of which alines with the adjacent wall of the recess 5, as clearly shown at the right 60 of Fig. 1.

The rails R are adapted to rest upon the bottoms of the recesses 5 and to extend partly over the depressions 6. Each of these depressions is adapted to receive a longitudinally channeled key or wedge 7, the channel being adapted to receive the inner base flange of the rail. The bottom of the wedge is adapted to rest in the depression 6 while the top thereof is designed to overhang the 70 inner base flange of the rail. The outer base flange of the rail will be engaged and overhung by the outer wall of the recess 5. When the wedge is positioned in the depression 6 it is driven longitudinally until it 75 binds tightly on the wall of the depression and also upon the inner base flange of the rail. The small end of the key is split longitudinally as at 8 and after the key has been driven to its proper position, the fingers 9 and 10 formed by splitting the end of the key are bent so as to prevent withdrawal of the key from the recess. Thus the rail will be held securely to the tie and cannot become separated therefrom until 85 after the fingers 9 and 10 have been straightened and the key withdrawn from the recess 5. By providing the slots 3, sufficient 90 resiliency is obtained to prevent the rails from breaking when subjected to the pounding action of the wheels passing thereover.

What is claimed is:—

A railway tie, comprising a web, there being base flanges at the ends of the web and extending a short distance longitudinally 95 thereof, there being top flanges overlying the inner ends of the base flanges, said top flanges provided with cut-away portions forming rail seats, and said web having notches communicating with the cut-away 100 portions for the reception of rail locking means and longitudinally extending slots overlying the base flanges.

In testimony that I claim the foregoing as my own, I have hereto affixed my signature in the presence of two witnesses.

HENRY W. HUFFMAN.
